COMBINED TISSUE DISPENSER AND LITTER
CONTAINER FOR AUTOMOBILES

Daniel C. Larkin, 3134 Woodstock Drive,
Detroit, Mich. 48221

Filed Mar. 30, 1965, Ser. No. 84,517

Term of patent 14 years

(Cl. D58—12.6)

FIG. 1 is a front perspective view of a combined tissue dispenser and litter container for automobiles, showing my new design;

FIG. 2 is a rear perspective view with the cover being partially open and a portion of a box of tissues being shown in broken lines for illustrative purposes only;

FIG. 3 is a side elevational view with the cover closed; and

FIG. 4 is a front elevational view thereof.

The side not shown is a mirror image of the side shown.

The dominant features of my design reside in the portion shown in full lines, including the appearance of the lid in combination with the container itself.

I claim:

The ornamental design for a combined tissue dispenser and litter container for automobiles, as shown and described.
